Filed July 10, 1972, Ser. No. 278,317

Term of patent 14 years

Int. Cl. D30—02

U.S. Cl. D30—2

FIG. 1 is a perspective view of a poultry house ventilation plenum showing my new design, an intermediate portion being cut away and omitted to indicate indeterminate length;

FIG. 2 is a top plan view, a portion being cut away and omitted to indicate indeterminate length;

FIG. 3 is a cross-sectional view taken on a line 3—3 in FIG. 1;

FIG. 4 is a fragmentary perspective view of the right end showing the triangular-shaped door in an opened condition; and

FIG. 5 is a right end elevational view thereof.

I claim:

The ornamental design for a poultry house ventilation plenum, as shown and described.
